CLAIM

The ornamental design for a mounting bracket for dead-end utility lines, as shown and described.

DESCRIPTION

FIG. 1 is a perspective view of a mounting bracket for dead-end utility lines illustrating the claim design.

FIG. 2 is a front view of the mounting bracket shown in FIG. 1.

FIG. 3 is a right side view of the mounting bracket shown in FIG. 1.

FIG. 4 is a left side view of the mounting bracket shown in FIG. 1.

FIG. 5 is a top view of the mounting bracket shown in FIG. 1.

FIG. 6 is a bottom view of the mounting bracket shown in FIG. 1; and,

FIG. 7 is a rear view of the mounting bracket shown in FIG. 1.

The broken lines showing portions of the mounting bracket for dead-end utility lines form no part of the claimed design.
